UNITED STATES PATENT OFFICE.

ARTHUR SMITHSON, OF GLENWOOD, MINNESOTA.

WAGON-POLE CONNECTION WITH SLEIGH-RUNNERS.

Specification of Letters Patent.

Patented Oct. 12, 1920.

1,355,705.

Application filed April 9, 1920. Serial No. 372,708.

To all whom it may concern:

Be it known that I, ARTHUR SMITHSON, a citizen of the United States, residing at Glenwood, in the county of Pope and State of Minnesota, have invented a new and useful Wagon-Pole Connection with Sleigh-Runners, of which the following is a specification.

This invention relates to runner attachments for wagons, and the main object is to provide new and improved device for connecting wagon poles and tongues of different sizes with the roller extending between the front ends of a pair of front runners. Another object is to show such device modified for connecting the short rear pole to the rear pair of runners. A third object is to show applied to one vehicle said two devices and also four of my improved brackets secured upon four runners for supporting the four skeins of the axles of a wagon box. Said brackets involving however an independent invention, I have simultaneously herewith filed a separate application for patent for them; and likewise a separate application for the device connecting the rear end of the rear pole, since that pole connection is considerably different from that herein shown on the front roller.

In the accompanying drawing:—

Figure 1 is a side elevation of a wagon box mounted upon front and rear runners by my improved brackets, or any other suitable brackets, and its regular pole or tongue attached to the front runners and its rear pole to the rear runners by my said two pole attaching device. Fig. 2 is a plan view of the runners and poles in Fig. 1, with the wagon box and its reach and axles omitted. Fig. 3 is an enlarged top view of the front roller and pole in Fig. 2. Fig. 4 is a left hand end view of Fig. 3. Fig. 5 is a bottom view of the metallic attaching means in Fig. 3, all wood work being omitted.

Referring to the drawing by reference numerals, 6 designates the box, 7 the reach, 8 and 9 the axles, and 10 the axle skeins of a wagon. Said skeins are supported in brackets 11, secured at 12 to the front runners 13 and rear runners 14. The improvement of the brackets and their peculiar skein thimbles 15 will be found fully described and

claimed in my said other application for such brackets.

Rotatably mounted in the heads or front ends of each pair of runners is the usual rollers 16 and 16^a. In the reach 7 is secured a bolt 17 having a bushing 18 between its head and the reach to space the head away from the reach. Said bushing forms the pivot in a short slot 18^a in the front end of a short pole 19 which assists in pulling and guiding the rear runners. Said pole 19 is secured by a bolt 20 in a channel-shaped iron 21 of a metallic coupling device 22, having also an inverted channel iron 23 secured by bolts 24 upon the rear roller 16 and connected by bracing webs 25 and 26 to the channel piece 21.

Bolted at 27 upon the front roller 16^a, is an inverted channel iron 28 (see near top of Figs. 2, 3 and 4). Only the end portions 29 and a short depressed portion 30 of the top of said channel iron 28 bear upon the wooden roller 16^a, the rest of the top is raised from the wood so as to form two cavities 31, 32, for the heads of bolts 33 and 34. The bolts 33 are movable in straight slots 35 in the top of the channel iron, and the bolts 34 are movable in segmental slots 36 in the channel iron and in straight slots 37 in D-shaped plates 38, on the top of which all of said bolts have nuts 39.

Said plates 38 have their outer edges 85 straight and bent upward and inward to form broad hooks 40. The wagon pole 41 is supposed to be removed from the hounds of the running gear of the wagon, where its broad rear end 42 is usually secured by a pivot bolt 43 slightly forward of the usual brace bar 44, and the main pole member 41 often has a depending rib 45.

Now, when the pole is removed from the wagon and attached to the roller 16^a of the front runner the said rib 45 is placed in the depression 30 as clearly shown in Fig. 4, and as shown in Figs. 2 and 3, the broad or fan-shaped part 42 of the pole is placed upon the plates 38 and secured by the bolt 100 43 after the hooks 40 are brought to engage over the edges of the wood 42 by moving of the plates 38 on the bolts 33, 34 and securing them by the nuts 39.

While the parts 28 and 38 may be cast from malleable iron or steel I prefer to drop-

forge and form them out of sheet steel as the article so made is light, strong and neat looking.

What I claim is:

- 5 1. The combination with a wagon pole or tongue and the roller of a pair of runners, of a coupling connecting said two elements, said coupling comprising a channel-shaped member secured upon the roller and embracing the sides thereof, two plates adjustably secured by bolts upon the channel iron and having broad hooks by which to engage over the opposite edges of the broad rear portion of the pole, and a bolt passed horizontally through said hooks and the pole.
- 10 2. The structure specified in claim 1, said channel iron having in its underside cavities for the heads of said bolts, it also having a longitudinal slot for one of the bolts in each

plate and a segmental slot for a second bolt 20 in each plate, and each plate having a longitudinal slot for the bolt in the segmental slot.

3. The structure specified in claim 2, said channel iron having in its top a transverse 25 depression and the pole having at its underside a rib occupying said depression.

4. In a structure of the kind described, a pair of runners, a roller connecting their front ends, a pole secured across the roller 30 by a metallic member; said member being bolted to the pole and the roller and having two rigidly secured crossing and reversely arranged channel portions fitting one upon the roller and the other the lower portion 35 of the pole.

In testimony whereof I affix my signature.
ARTHUR SMITHSON.
